ROADSIDE VENDING STAND

Dominick Perez, Elmhurst, N. Y.

Application October 3, 1956, Serial No. 43,225

Term of patent 14 years

(Cl. D13—1)

Fig. 1 is a front elevational view of a roadside vending stand embodying my new design;

Fig. 2 is a side elevational view thereof, the other side being the same;

Fig. 3 is a rear elevational view with a portion of the handle broken away; and

Fig. 4 is a top plan view.

I claim:

The ornamental design for a roadside vending stand, as shown and described.
